(57) **CLAIM**

The ornamental design for the fishing rod holder, as shown and described.

DESCRIPTION

FIG. 1 is a front elevational view of the fishing rod holder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of thereof taken from above and to the left;

FIG. 8 is a front elevational view of an alternatively preferred embodiment of the fishing rod holder showing my new design;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a perspective view of thereof taken from above and to the left.
